UNITED STATES PATENT OFFICE.

ALLEN C. MARTIN, OF RALSTON, WASHINGTON.

EXTENSION-WRENCH.

1,335,590.

Specification of Letters Patent. Patented Mar. 30, 1920.

Application filed March 20, 1917, Serial No. 156,035. Renewed February 24, 1920. Serial No. 880,759.

To all whom it may concern:

Be it known that I, ALLEN C. MARTIN, a citizen of the United States, and a resident of Ralston, in the county of Adams and 5 State of Washington, have invented certain new and useful Improvements in Extension-Wrenches, of which the following is a specification.

One of the principal objects of my invention is to provide an improved extension wrench in which the jaws may be quickly and with little effort extended and adjusted to the size of the work, the construction being such that the wrench may be readily manipulated by one hand, and may be instantaneously adjusted.

A further object of the invention is to provide an improved wrench of the class described, which will be characterized by 20 advantages of simplicity, durability, efficiency in operation and economy in manufacture.

With these and other objects in view, which will become apparent as the description proceeds, the invention resides in the construction, combination and arrangement of parts hereinafter more fully described and claimed, and illustrated in the accompanying drawings in which like characters of 30 reference indicate like parts through the several figures, of which

Figure 1 represents a side elevational view, partly in section, of a wrench constructed according to my invention, the jaws being shown in one position in full lines 35 and in another position in dotted lines.

Fig. 2 represents a view in section taken transversely on the plane indicated by the line A—A of Fig. 1.

Fig. 3 represents a similar view taken on 40 the plane indicated by the line B—B of Fig. 1.

In carrying out my invention I form the jaws 1, each at the outer end of one of the arms 2, there being a pair of such arms. 45 These arms taper toward their inner ends and are pivotally connected together as at 3, the arms being movable toward and away from each other about the pivot point 3. Interposed between the arms 2 is a leaf 50 spring 4 which at one end is connected to one of the arms and at its other end bears against the opposite arm, the tension of the spring normally acting upon the arms for 55 spreading them apart.

One of the arms 2 is provided on its outer

side with a plurality of notches 5 which are a suitable distance apart and are of suitable dimensions, and these notches are adapted to coöperate with a lug 10 formed 60 on the casing 6 in retaining the arms and jaws in adjusted position.

This casing slidably receives the arms 2 and tapers toward its outer and smaller end. This end may be rounded as at 7 to 65 form a convenient hand grip. The inner and larger end 8 of the casing is thickened, whereby to provide a strong construction, and the lug 10 is cast on the casing at its larger end near the entrance to the casing, 70 as clearly shown. The side walls of the casing are provided with longitudinal slots 9 through which the outer ends of the pivot pin 3 extend. These ends do not extend beyond the outer surfaces of the casing, but are 75 adapted to slide in the slots, thus guiding the arms 2 in their movements longitudinally of the casing.

It will be readily understood that when the jaws 1 are engaged with a nut or other 80 work, and the casing is locked relatively to the arms by engagement of the lug 8 with one of the notches 5, the arms and jaws will be held against slipping and the work will be effectively held between the jaws for 85 manipulation.

The wrench being in the position with the jaws retracted, as indicated in full lines in Fig. 1, and it being desired to engage a larger piece of work, the casing or handle 90 may be grasped in one hand with the jaw on which the notches 5 are arranged upwardly, and then by throwing the hand outwardly and downwardly, the jaw will be disengaged from the lug 10 and this will 95 cause the arms to move to the outward extent of their path of movement. The jaws will then be jammed on the nut, pipe or other work, and the adjustment of the jaws to the work will take place automatically 100 by reason of the fact that the casing will move upwardly along the arms 2 until the larger reinforced end of the casing will jam around these arms. The lug 10 will have engaged with one of the notches 5 for retaining the jaws in their adjusted position.

Shoulders 11 are formed at the inner ends of the jaws 1 and bear against the outer end of the casing 6 when the jaws are in their 110 fully retracted position. These shoulders limit the inward movement of the arms so that there will be no danger of their being

jammed into the smaller end of the casing, and the shoulders also act as reinforcements for the jaws when the latter are in their retracted position.

5 Although I have described the preferred embodiment of my invention, I may desire to make such changes in the construction, combination and arrangement of parts thereof as do not depart from the spirit of 10 the invention and the scope of the appended claim.

I claim:

An extension wrench of the class described including a casing forming a handle, a pair 15 of jaws each including an arm, said arms

being pivotally connected together for relative angular movement and being arranged slidably in the casing, spring means interposed between the arms normally tending to move them apart, a pivot pin which connects the arms, said pin having its ends arranged for movement within longitudinal slots provided in the casing, a lug formed integrally with the casing internally of its open end, and a longitudinal series of transverse notches formed on one of the arms 25 coöperating with the lug in maintaining the jaws in adjusted position.

A. C. MARTIN.
